UNITED STATES PATENT OFFICE.

ALBERT W. JOHNSTON, OF NEW YORK, N. Y., ASSIGNOR TO THE S. S.
WHITE DENTAL MANUFACTURING COMPANY, OF PHILADELPHIA,
PENNSYLVANIA.

DESIGN FOR A TOOL-HANDLE.

SPECIFICATION forming part of Design No. 31,825, dated November 14, 1899.

Application filed October 17, 1899. Serial No. 733,938. Term of patent 14 years.

To all whom it may concern:

Be it known that I, ALBERT W. JOHNSTON, a citizen of the United States, residing at New York, (New Brighton,) in the county of Richmond and State of New York, have invented 5 a certain new and useful Design for a Tool-Handle; and I do hereby declare the following to be a full, clear, and exact description of the invention, such as will enable others 10 skilled in the art to which it appertains to make and use the same.

The leading feature of my design for a tool-handle consists of the middle portion, which is octagonal in cross-section and has straight 15 parallel longitudinal sides, the front portion, which is round in cross-section and has a compound longitudinal curve, and the rear portion, which is also round in cross-section and tapers slightly toward its rear end.

20 The design is illustrated in the accompanying drawings, in which—

Figure 1 is a view in elevation of the improved design; and Figs. 2, 3, and 4 are cross-sectional views on the lines 2, 3, and 4, re- 25 spectively, of Fig. 1.

To more particularly describe my design, I will say that it may be divided into three nearly-equal portions—namely, the middle portion A, the front portion B, and the rear portion C. The middle portion A is octagonal in 30 cross-section and has straight parallel longitudinal sides *a*. The front portion B is round in cross-section and its sides are in the form of a compound longitudinal curve—that is to say, the sides converge or curve inwardly at 35 *b*, swell or curve outwardly at *b'*, and then again converge or curve inwardly at the front extremity *b*². The rear portion C is also round in cross-section and tapers slightly toward its rear extremity *c*. 40

I claim as my invention—

The design for a tool-handle, as herein shown and described.

In testimony whereof I affix my signature in presence of two witnesses.

ALBERT W. JOHNSTON.
